UNITED STATES PATENT OFFICE.

DONAT GERVAIS, OF STOCKHOLM, MAINE.

SAFETY GATE FOR PULP VATS.

Application filed February 18, 1927. Serial No. 169,331.

This invention relates to new and useful improvements in gate structures, and has more particular reference to a safety gate primarily adapted for use in conjunction 5 with pulp vats.

The primary object of the invention resides in the provision of a normally closed gate that is so constructed as to be automatically opened during the rolling of a log 10 into the vat, which log forcibly strikes against the gate for opening the same.

A further and important object is to provide a gate structure of this character wherein as the log passes therethrough the 15 same will automatically return to closed position and at the same time become automatically locked in such position.

This character of gate is especially adapted for use in veneer mills wherein logs are 20 thrown into the vats. Such vats are now protected at three sides, but the side through which the logs pass is in every instance that has invited my attention, open and frequently the workmen will fall into the vats 25 through these openings with the resultant loss of life.

In the drawing wherein like numerals indicate corresponding parts throughout the several views:

30 Figure 1 is a top plan view of a vat platform beneath the opening in which is the usual vat, not disclosed, said vat platform being equipped with a safety gate constructed in accordance with the present invention,

35 Figure 2 is a longitudinal section taken substantially upon the line 2-2 of Figure 1, and

40 Figure 3 is an enlarged fragmentary view partly in elevation and partly in cross section through one of the locking members of the mechanism disclosing the lower end of the gate as held thereby.

Now having particular reference to the drawing, 5 indicates the usual platform in 45 position above a pulp vat, not disclosed, said platform being provided with the usual rectangular opening 6 above the vat through which the logs are thrown. In carrying out my invention there is arranged at the four

50 corners of this opening six vertical posts 7, the rear two of which are interconnected by a cross bar 8 while the end posts are interconnected by short bars 9-9.

Furthermore, there is arranged across the 55 rear posts 7 a metal strap 10, the ends of

which pass between the adjacent end posts and are connected at their ends to the front posts 7-7 in any suitable manner. Furthermore the front posts 7-7 are interconnected at their upper ends by a cross bar 11. 60

The construction just described with the possible exception of the forward bar 11 is more or less of conventional construction and I do not desire to lay any particular stress thereon. This construction is merely 65 disclosed and briefly described so as to lay a foundation for the illustration and description of my particular invention.

Said invention consists of a suitable gate 12 of a length slightly less than the length 70 of the bar 11 and suitably pivotally suspended from said bar as suggested in Figure 1. This bar is formed or provided at its forward side with two or more laterally projecting pins 13-13 while the gate 12 is 75 also formed or provided with similar pins 14 beneath said first mentioned pins and interconnecting which are retractile coil springs 15 for the purpose of normally swinging the gate to the position more clearly disclosed in Figure 2, in which position the passage between the front posts 7-7 is 80 closed.

Arranged horizontally upon the platform 85 5 adjacent the ends of the gate 12 is a pair of spaced parallel and inclined leg skid bars 16-16 upon which the logs being fed to the vat will roll as indicated by the dotted lines in Figure 2. Pivoted to the platform 5 within said skid bars 16-16 and parallel therewith are trip levers 17-17 preferably of flat-like bar formation, and throughout the major portion of their area beneath their upper surface of said skid bars 16-16. The ends of these trip levers adjacent the gate 90 12 are curved upwardly as 18-18 above the skid bars, so as to be encountered by the lugs as the same pass over the bars just prior to their entrance into the vat. Each trip lever is maintained in such position by 95 reason of a small expansible coil spring 19 resting upon the platform and within a socket 20 formed in the underside of each lever. 100

At the extreme inner end of each lever 17 the same is formed with a depending cup 21 within which is arranged a small expansible coil spring 22 for the purpose of maintaining a small beveled latch pin 23 projecting through an opening in the lever 110

as clearly indicated in Figure 3. The latch pins of these levers are obviously for the purpose of preventing the accidental inward movement of the gate 12 when the same has been forcibly swung to a rearward closed position as indicated in both Figures 2 and 3. For limiting the rearward swinging movement of the gate, each lever 17 is provided with a vertical pin 24 in spaced relation with respect to the latch pin 23.

Obviously as the log rolls down the skid bars 16-16, the upwardly bent ends 18-18 of the trip levers 17-17 will be encountered and the weight of the logs will swing said levers downwardly for releasing the gate. Furthermore, the force of the logs will move the gate inwardly in the direction of the arrow in Figure 2 so that the logs will move through the opening in the platform into the vat. Immediately upon the logs passing from the levers, the same will be raised by reason of the coil springs 19 so that when the gate 12 is returned under action of the springs 15, the same will lock between the latch pins 23 and the stop pins 24.

In view of the foregoing description when considered in conjunction with the accompanying drawing, it will be apparent that I have provided a highly novel, simple and efficient safety gate for pulp vats that is well adapted for all the purposes heretofore designated, and even though I have herein shown and described the invention as consisting of certain detail structural elements, it is nevertheless to be understood that minor changes may be made therein without affecting the spirit and scope of the appended claims.

Having thus described the invention, what I claim as new is:

1. In automatic gate, a swingingly mounted gate structure, yieldable means for normally swinging the gate to closed position, and trip means for releasably securing the gate, comprising a gate engaging member arranged for disengagement upon contact by a moving object traveling in a direction toward the gate, said trip means further including a latch permitting return of the gate to a closed position and preventing opening of the gate except through the operation of said gate engaging member.

2. In an automatic gate, a swingingly mounted gate structure, said gate being normally operable toward a closed position and gate retaining means for securing the gate in closed position and arranged for releasing the gate upon contact by an object moving in a direction toward the gate, the continued movement of the objects operating to

open said gate by direct engagement therewith.

3. In an automatic gate, a gate supporting platform having an opening therein, a gate swingingly mounted upon the platform adjacent one side of the opening, yieldable means for normally swinging the gate to closed position, and means associated with the platform for releasably securing the gate in closed position, said means being actuated by contact therewith of a moving object traveling in a direction toward the gate, the continued movement of the object operating to open the gate by direct engagement therewith, permitting said object to enter the opening in the platform.

4. In an automatic gate, a gate supporting platform having an opening therein, a swingingly mounted gate upon the platform adjacent one side of the opening, means for normally swinging the gate to closed position and means associated with the platform for releasably securing the gate in said position, said means being releasable by contact of a gravity actuated object passing thereover and subsequently engaging the gate for opening the same.

5. In an automatic gate, a gate supporting platform having an opening therein, a swinging gate mounted upon the platform adjacent one edge of the opening and adapted to swing to normally closed position, a lever pivoted to the platform and having means at one end for locking the gate in closed position, and means formed as a part of the lever adapted to be encountered by a gravity actuated object for passing thereover and releasing the gate from the lever, said gate being arranged in the path of movement of the object and directly engageable thereby for opening the same.

6. In combination, a gate supporting platform having an opening therein, a gate swingingly mounted adjacent the opening, a gravity runway leading toward the gate, means yieldably urging the gate in closed position, a pair of levers pivotally mounted on the platform and arranged at opposite sides of the gate, latch means at one end of each of the levers releasably retaining the gate in closed position, yieldable means normally urging the latch end of the lever toward engagement with the gate, said levers being arranged in the path of objects moving on said runway and adapted for latch releasing operation upon contact thereby, the continued movement of said objects operating subsequently to engage and open said gate.

In testimony whereof I affix my signature.
DONAT GERVAIS.
